(57) CLAIM

The ornamental design for a parka, as shown and described.

DESCRIPTION

FIG. 2 is a front elevation view of the parka of the invention.

FIG. 3 is a left side elevation view of the parka of the invention.

FIG. 4 is a right side elevation view of the parka of the invention.

FIG. 5 is a top plan view of the parka of the invention; and,
FIG. 6 is a bottom plan view of the parka of the invention.
The broken lines are for the purpose of illustrating portions of the article and form no part of the claimed design.

1 Claim, 4 Drawing Sheets
